UNITED STATES PATENT OFFICE.

JOHN JEFFERSON KENYON, OF DETROIT, MICHIGAN.

WASHING MACHINE.

Application filed February 16, 1922. Serial No. 536,933.

To all whom it may concern:

Be it known that I, JOHN JEFFERSON KENYON, a subject of the King of Great Britain, residing at the city of Detroit, in the county of Wayne, in the State of Michigan, United States of America, have invented certain new and useful Improvements in Washing Machines, of which the following is the specification.

10 My invention relates to improvements in washing machines and the object of the invention is to improve the construction of a washing machine of this type as will not only more thoroughly wash the clothes but 15 also require less power than the machines at present in use.

A further and most important object is to so construct the machine that there will be no necessity of turning the clothes once 20 they are placed in the machine.

A still further object is to more readily release the vacuum cups from contact with the clothes and thereby obviate the necessity of having to release the vacuum cups in 25 order that the clothes may be turned.

To effect these objects my invention consists of a supplemental bottom located slightly above the ordinary bottom and preferably of an open work construction, such 30 as wire mesh or a like construction, adapted to produce the same results and which co-acts with the vacuum cups in the manner, which I shall presently describe.

Fig. 1 represents a perspective view of 35 my washing machine, the side being broken away to disclose the interior.

Fig. 2 is a plan view of the washing machine with the top removed, one of the vacuum cups and the perforated false bottom being broken away to expose the arms on which the perforated false bottom is seated.

Fig. 3 is an elevational view of a broken away portion of the interior of the machine, 45 showing the action of one of the vacuum cups on the clothes contained therein.

Like characters of reference indicate corresponding parts in the different views.

1 is the washing machine. 2 is the drum 50 thereof. 3 are the legs. 4 is a vertical sleeve extending upwardly through the centre of the bottom 5 of the drum. 6 are diametrically positioned vacuum cups mounted on the extremities of the arms 7 55 which are secured to the rod 8 in the vicinity of its upper end, said rod being

housed in the sleeve 4 and pivotally connected at its lower end to the oscillating arm 9.

10 is a perforated false bottom, seated on the radially extending arms 11 which are provided with the sluice holes 12, said arms being secured at their inner ends to the sleeve 4, and at their outer ends to an annular ring 13, which fitting tightly around 60 the interior periphery of the bottom of the drum, serves the dual purpose of rigidly securing the arms 11 and supporting the perforated bottom 10.

The operation of the device is as follows:

My vacuum washing machine operates in the customary manner, that is, the rod 8, and consequently the vacuum cups 6 are given a vertical reciprocating movement 75 through the medium of the oscillating arm 9, which is pivotally connected to the lower extremity of the said rod 8. The oscillating arm being actuated by any suitable power or manual means.

80 In the machines at present in use, the vacuum cup or cups compress the clothes into a compact mass in the bottom of the drum, thus preventing a cleansing flow of water underneath and through the clothes, 85 and at the same time through the inaction of the water create such a vacuum that the clothes cling to vacuum cups through the greater part of each stroke, thus wasting a great deal of power and time. I have 90 overcome this defect by inserting a perforated false bottom in the drum, the bottom being preferably constructed of stout galvanized iron netting or any suitable perforated or netted material. This false bottom 95 is seated on the annular rim 13 and the arms or supports 11. These arms are provided with the sluice holes 12, thus allowing a perfect circulation of water.

From this construction it will readily be 100 seen that the upper movement of the vacuum cups draws the water from underneath the false bottom up through the clothes, and expels it on the return stroke, thus ensuring a continuous stream of water through the 105 clothes throughout the whole washing operation. In washing machines of the vacuum cup type it is the general practice to give the vacuum cups a rotary as well as a vertical movement in order to bring the 110 cups in contact with the whole upper portion of the clothes. The resultant action

of this rotary movement is provided for in my device by the sluice-holes 12 which allow the water to constantly flow, that is, when the water is withdrawn through the clothes from one section it is immediately replaced by water flowing downwardly through the clothes at another point.

From the above it will be seen that I have devised a means of keeping the water 10 in constant circulation through the clothes in the machine, thus insuring an even cleansing.

What I claim as my invention is:

In a washing machine, the combination 15 with a tub, of a ring resting on the bottom of the tub and having an inwardly ex-

tending top flange, a sleeve disposed in the centre of the ring and extending through the bottom of the tub, a plurality of arms extending between the sleeve and the ring, 20 a circular perforated false bottom supported on the arms and the inwardly extending flange of the ring and a rod extending through said sleeve and carrying vacuum cups above said false bottom.

Signed at Toronto this 28th day of January 1922.

JOHN JEFFERSON KENYON.
